UNITED STATES PATENT OFFICE.

GEORGE ROUNDS HICKS, OF PERRYSVILLE, INDIANA.

SAWBUCK.

No. 826,426.

Specification of Letters Patent.

Patented July 17, 1906.

Application filed January 13, 1906. Serial No. 295,973.

To all whom it may concern:

Be it known that I, GEORGE ROUNDS HICKS, a citizen of the United States, residing at Perrysville, in the county of Vermilion 5 and State of Indiana, have invented a new and useful Sawbuck, of which the following is a specification.

This invention relates to sawbucks, and has for its object to provide improved means 10 for retaining the log or other material in position on the sawbuck during the sawing operation without requiring the operator to hold his knee upon the log.

A further object of the invention is to provide a log-engaging member movable to operative position by a foot-operated lever or treadle, and, further, to provide an auxiliary lever for forcing said member into engagement with the work.

20 A still further object of the invention is to generally improve this class of devices so as to add to their utility and durability as well as to reduce the cost of manufacture.

With these and other objects in view the 25 invention consists in the construction and novel combination and arrangement of parts hereinafter fully described, illustrated in the accompanying drawings, and pointed out in the claims hereto appended, it being understood 30 that various changes in form, proportions, and minor details of construction may be resorted to without departing from the principle or sacrificing any of the advantages of this invention.

35 In the accompanying drawings, forming a part of this specification, Figure 1 is a perspective view of a sawbuck constructed in accordance with my invention and showing in dotted lines the initial position of the foot- 40 lever and log-engaging member. Fig. 2 is a vertical sectional view of the casing and locking-pawl. Fig. 3 is a side elevation of the foot-lever and a portion of the log-engaging hook. Fig. 4 is a side elevation of a sawbuck, 45 illustrating a modified form of log-engaging hook. Fig. 5 is a transverse sectional view taken on the line 5 5 of Fig. 4. Fig. 6 is a detail perspective view of the pivoted end of the hook, showing the manner of mounting 50 the spring.

Similar numerals of reference indicate corresponding parts in all the figures of the drawings.

The improved sawbuck consists of the supporting-brackets or cross-legs 5, provided

with alined crotches 6, adapted to receive the log or other work 7 and connected by a longitudinal bar or brace 8, upon which is mounted for sliding movement an auxiliary bracket or log-support 9.

60

Mounted for pivotal movement on a longitudinal rod 10, connecting the lower ends of the cross-arms, is a foot-operated lever or treadle 11, said treadle being secured in position by suitable clips 12 and having its free end reduced and provided with a vertical lug 13, formed with a slot or recess 14. Secured to one longitudinal edge of the treadle 11 is one end of a spring 15, the opposite end of which is fastened to the adjacent cross-leg 5, 70 while its intermediate portion is coiled around the rod 10 and serves to normally hold the free or reduced end of the treadle in elevated position. The arm or extension 16 of the spring is preferably held in contact with a laterally-extending pin 17 on the treadle by means of headed studs or pins 19, arranged one on each side of the pin 17, as shown. Pivoted at 20 in the slot 14 is the curved end 21 of a rack-bar 22, upon which is slidably mounted for vertical movement a casing 23, carrying a projection or lug 24 and a pawl 25, the pawl 25 being held in yieldable contact with the teeth on the rack-bar by means of a coiled spring 26, interposed between the 80 handles 27. Rigidly secured to the casing 23, as by bolts or similar fastening devices 28, is a log-engaging member 29, the free end of which terminates in a laterally-extending hook 30, adapted to impale the log or other 90 work to be operated upon, as will be more fully explained hereinafter.

The treadle 11 is formed with a longitudinal slot or recess 31, and disposed within said slot and pivotally mounted on the pin 17 95 is a foot-operated lever 32, the long end of which is provided with a vertical extension or lip 33, adapted to engage and elevate the curved end of the rack-bar, while the opposite of short end of said lever extends above 100 the general horizontal plane of the treadle and is formed with a terminal extension or lug 34, adapted to be depressed by the heel of the operator.

In operation the log or other work to be 105 operated upon is seated in the crotches of the cross-legs, after which the log-engaging member is moved to operative position by depressing the treadle and said member adjusted vertically to accommodate the log by 110

releasing the pawl 25 and sliding the casing 23 on the rack-bar. The short end of the lever 32 is then depressed by the foot of the operator, which causes the long end thereof to 5 elevate the curved end of the rack-bar and force the bill of the hook 30 into the log. When it is desired to release the log to permit the latter to be adjusted longitudinally within the crotches, the foot is removed 10 from the treadle, the coiled spring serving to withdraw the hook from the log and return the treadle to elevated or inoperative position.

In Figs. 4 to 6, inclusive, of the drawings 15 there is illustrated a modified form of the invention in which the foot-operated lever 32 is dispensed with, the log-engaging member 29' being formed of a continuous rod or bar, having an eye 35 in one end thereof and provided with a transversely-disposed pin 36. 20 In this form of the device the free end of the treadle 11' is provided with a slot or recess 37 for the reception of terminal eye 35 of the member 29' and through which passes a 25 pivot pin or bolt 38, as shown. As a means for yieldably supporting the free end of the rod 29' in engagement with the work when the treadle is in elevated or inoperative position there is provided a suitable spring, pref- 30 erably formed from single piece of spring- wire, an intermediate portion of which is bent to form a closed loop 39, which bears against the pivoted end of the rod 29', while its opposite ends are coiled around the trans- 35 verse pin 36 at 40 and extended to form terminal spring-arms 41 for engagement with the free end of the treadle. It will thus be seen that the rod 29' is normally supported in yieldable contact with the log or other 40 work, so that when the treadle 11' is depressed the active end of the rod will be drawn downwardly into engagement with the log, and thus prevent the latter slipping during the sawing operation.

45 It will of course be understood that the bill of the log-engaging hook in either form of the device may be so proportioned as to embrace the top of the log or to impale the latter, according to the size and shape of the 50 work being operated upon. It will also be understood that by adjusting the auxiliary support 9 longitudinally of the cross-beam 8 short sections of logs may be conveniently 55 operated upon without danger of the log tilting, so that the entire log may be conveniently cut or severed into predetermined lengths.

I claim—

60 1. The combination with a sawbuck, of a treadle, a pivoted work-engaging member carried by the treadle and movable to operative position when the treadle is depressed, means carried by the treadle and engaging the pivoted end of the work-engaging mem- 65 ber for actuating said member to grip the

work, and means for moving the member to inoperative position when the treadle is released.

2. The combination with a sawbuck, of a treadle, a work-engaging member carried by 70 the treadle and movable to operative position when the treadle is depressed, a lever pivoted to the treadle and adapted to engage said member for forcing the latter into engagement with the work, and means for 75 moving said member to inoperative position when the treadle is released.

3. The combination with a sawbuck, of a treadle, a vertically-adjustable work-engaging member carried by the treadle and mov- 80 able to operative position when the treadle is depressed, a foot-operated lever pivoted to the treadle and adapted to engage said mem- 85 ber for forcing the latter into engagement with the work, and means for moving said member to inoperative position when the treadle is released.

4. The combination with a sawbuck, of a treadle, a work-engaging hook pivotally mounted on the treadle and movable to operative 90 position when the treadle is depressed, and a foot-operated lever carried by the treadle for forcing the bill of the hook into engagement with the work.

5. The combination with a sawbuck, of a 95 treadle, a work-engaging member pivotally mounted on the treadle and movable to operative position when the treadle is depressed, said member having one end thereof extended to form a lateral arm, and its opposite end 100 provided with a terminal hook, and a foot-operated lever carried by the treadle and adapted to engage the lateral arm for forcing the bill of the hook into engagement with the work.

6. The combination with a sawbuck, of a treadle provided with a longitudinal slot, a work-engaging member pivotally mounted on the treadle and movable to operative position when the treadle is depressed, and a 110 foot-operated lever pivotally mounted in said slot and adapted to engage said member for forcing the latter into engagement with the work.

7. The combination with a sawbuck, of a 115 treadle provided with a longitudinal slot, of a work-engaging member pivotally mounted on the treadle and having one end thereof ex- 120 tended to form a lateral arm and its opposite end provided with a terminal hook, and a foot-operated lever mounted for pivotal movement in said slot and adapted to engage the lateral arm for forcing the bill of the hook into engagement with the work.

8. The combination with a sawbuck, of a 125 treadle pivotally mounted thereon and pro- 130 vided with a longitudinal slot, a rack-bar pivoted to the treadle and having its pivoted end extended laterally to form an arm, a casing slidably mounted on the rack-bar and pro-

vided with a pawl for engagement with the teeth on said rack-bar, a hook carried by the casing, and a lever pivotally mounted in said slot and adapted to engage the lateral arm 5 for forcing the bill of the hook into engagement with the work.

9. The combination with a sawbuck comprising a plurality of spaced supporting-brackets connected by a longitudinal bar, of 10 a treadle mounted for pivotal movement on said rod, a work-engaging member carried by the treadle and movable to operative position when the treadle is depressed, a foot-operated lever pivotally mounted on the treadle 15 and adapted to force said member into engagement with the work, and a spring coiled around the longitudinal bar and having its opposite ends connected to the treadle and the adjacent supporting-bracket, respectively, for returning said member to inoperative position when the treadle is released.

10. The combination with a sawbuck, comprising spaced supporting-brackets connected by longitudinal bars of a detachable 25 treadle, clips embracing one of the longitudinal bars and engaging the treadle a work-engaging member pivotally mounted on the treadle and movable into engagement with the work when the treadle is depressed, and a

spring coiled around the treadle-supporting 30 bar and having its opposite ends secured to the treadle and adjacent supporting-brackets respectively for moving the member to inoperative position when the treadle is released.

11. The combination with a sawbuck 35 comprising a plurality of spaced supporting-brackets connected by longitudinal bars, of an auxiliary bracket mounted for sliding movement on one of said bars, a treadle pivoted to the other bar and provided with laterally-extending pins, a work-engaging member pivotally mounted on the free end of the treadle and movable to operative position when the treadle is depressed, and a spring coiled around one of said bars and having one 40 end thereof threaded between the pins and its opposite end connected to the adjacent supporting-bracket for returning said member to inoperative position when said treadle is released.

50 In testimony that I claim the foregoing as my own I have hereto affixed my signature in the presence of two witnesses.

GEORGE ROUNDS HICKS.
